UNITED STATES PATENT OFFICE.

HERMANUS VAN RIJMENAM, OF THE HAGUE, NETHERLANDS.

ASSEMBLING COVER.

Application filed February 12, 1923. Serial No. 612,558.

To all whom it may concern:

Be it known that I, HERMANUS VAN RIJ-
MENAM, manufacturer, a subject of the
Queen of the Netherlands, residing at The
5 Hague, Netherlands, have invented certain
new and useful Improvements in Assem-
bling Covers, of which the following is a
specification.

The invention relates to assembling covers
10 previously prepared in which loose folios,
fourth parts of a quire, catalogues, pieces of
music and the like may be attached.

All these assembling covers have, however,
one of the following disadvantages depend-
15 ent on the manner in which they are con-
structed. In the first place it is often im-
possible to see each page entirely up to the
back of the cover, for the reason that the
cover exerts a clamping-action on the leaves.
20 In this case the cover has to be kept open by
hand in order to prevent the leaves from
turning over.

Another disadvantage of other assem-
bling covers consists in that the parts to be
25 assembled are provided with holes, which
injury may be troublesome in particularly,
when it is desired later on to loosen the
pieces for having them bound together.

These disadvantages come in particular
30 to the fore when loose pieces of music are
assembled in an assembling cover.

The book must e. g. be placed on the piano
and then it is exceedingly difficult when each
35 page can not be turned over at will and re-
mains open, or when the portion of the
page nearest to the back of the book can not
be seen entirely.

The invention has for its object to pro-
vide an assembling-cover previously pre-
40 pared in which the above mentioned disad-
vantages are entirely removed and in which
consequently fourth parts of a quire may be
attached in such a manner, that without in-
juring the parts the pieces inserted may be
45 laid open entirely and retain this position.

The invention therefore consists of an as-
sembling cover for loose pieces of music, il-
lustrations, periodicals, and the like in
50 which the various pieces to be assembled
may each be attached separately.

According to the invention the back of
the cover is shaped as a case within which
an elastic mass is contained and kept en-
closed by means of a cover- or closing-strip,
55 while the pieces to be assembled are attached
to the mass by means of pins or staples.

In the accompanying drawing a cover ac-
cording to the invention is illustrated by
way of example.

Fig. 1 is an elevation in perspective. 60

Fig. 2 is a partial sectional view.

Fig. 3 is a clamp for attachment.

Fig. 4 is a view in perspective of an open
lying fourth part of a quire with attachment
clamps placed thereover. 65

Fig. 5 is a point of a clamp on a much
larger scale.

In these figures 1 is the back of the cover,
which is here formed as a flat case. 2 are
the leaves of the cover. The case 1 is filled 70
with some solid but elastic mass 3 for which
preferably cork is used. This cork is kept
enclosed within the back by a covering strip
4 of linen or similar material. The manner
in which these separate pieces are secured 75
to the elastic mass, has also been shown in
the drawing, 5 indicates the leaf to be insert-
ed, 6 are the staples by means of which the
attachment is effected. The staples are
pressed by hand into the cork and have suf- 80
ficient resisting capacity for holding the
bound leaves securely. Although not neces-
sary it is advisable to roughen the point 8
of the staples at the outer side by small
notches or in any other suitable way (see 85
Fig. 5). The frictional resistance is hereby
increased when pulling out the staples,
while no injury of the leaves or the cork is
caused, when a piece is removed from the
cover. 90

The entire width of the back may be used
for inserting leaves, while further by suit-
able arrangement of the staples in two ad-
jacent fourth parts of a quire, that is to say
by placing the latter in staggered relation 95
longitudinally, these fourth parts of a quire
may be inserted very close to each other.

Instead of staples having two points, pins
having a single point or staples having more
than two points may also be used. It is 100
also possible to give the back of the cover
another shape and to make other modifi-
cations within the scope of the invention.

Having now particularly described and
ascertained the nature of my said invention,
what I claim as new and desire to secure by
Letters Patents is:

1. An assembling cover comprising a back
portion; a mass of cork in said back portion;
and means for securing said mass in said 110
portion.
2. An assembling cover comprising a back

- portion; and an elastic material in said back portion adapted to removably receive staples.
3. An assembling cover having its back 5 shaped as a case, a mass of cork contained in this case, a linen closing strip for keeping the cork enclosed in the case, and staples for securing in the cork the pieces to be assembled.

4. An assembling cover comprising a back 10 portion; an elastic material in said back portion; cover leaves secured to said back portion; and means for securing said material in said portion and secured to said leaves, said elastic material being adapted 15 to removably receive staples.

In testimony whereof I affix my signature.
HERMANUS VAN RIJMENAM.
